PRINTING MACHINES

Francis Ralph Patalon, Euclid, Ohio, assignor to Addressograph-Multigraph Corporation, Cleveland, Ohio, a corporation of Delaware

Application February 13, 1958, Serial No. 715,036

8 Claims. (Cl. 101—91)

This invention relates to a new and improved offset printing machine and more particularly to an offset printing machine which permits printing, in a single operation, of both variable and fixed data.

The popularity of offset printing machines is well known. Machines of this kind are widely utilized for general duplicating requirements, including the preparation of circulars, inter-office communications, reports, charts, and the like. Because of the ease and facility of operation and the high quality of prints produced, planographic offset duplicating machines have also been widely used for printing letterheads, drawings, and even for three-color process work. Copy reproduced on machines of this kind lasts indefinitely, each duplicate copy retaining the appearance and the qualities of the original.

The lithographic masters utilized in offset printing machines, although originally made of zinc or aluminum, are now to a great extent made of specially prepared paper. The paper masters afford many important advantages, including easier typing, proof reading, and correcting, and also are moderate in price as compared with metal masters. Paper masters of this kind comprise a high wet strength paper to which an appropriate coating is applied; a preferred form of lithographic master and the method of preparing such masters is described in detail in United States Letters Patent No. 2,534,650 to S. Worthen, issued December 19, 1950. These paper-base lithographic masters may be provided with perforated areas permitting detachment of portions thereof to afford a means for removing a part of the master in the reproduction of certain kinds of data. There are also "stick on" and "overlay" masters which may be attached to an original master at predetermined places in those applications where it is desired to add to or to alter portions of the original copy. The versatility of offset printing machines is also enhanced by devices for automatically applying the starting solution to the master and for applying a cleaner solution to the offset cylinder blanket immediately upon the completion of a printing run. Other known arrangements permit the mounting of two or more masters on the form cylinder of the offset printing machine, thereby affording another means for adding or deleting portions of the printed information.

The relatively versatile operation made possible by the aforementioned devices and developments with respect to rotary planographic printing machines makes possible their use for highly variable and exacting applications, provided some means may be afforded for the selection of different areas or lines of data on consecutive printing operations. Thus, an offset printing machine which incorporates means for selecting particular portions of the data on the master cylinder for successive printing operations may be utilized in the preparation of production orders and in other short-run printing operations in which it is necessary to reproduce some of the data consistently and to change other portions of the data. Of course, the offset printing machine

2

affords the same advantages in connection with applications of this kind as in more conventional duplicating and printing operations.

A principal object of the invention, therefore, is a new and improved offset printing machine including a novel means for varying the content of the printed data.

Another object of the invention is a new and improved offset printing machine which affords a convenient and effective means for modifying a portion of the printed data with each printing operation or after any desired number of printing operations.

A more specific object of the invention is a new and improved offset printing machine including a blanket cylinder comprising means for changing the data printed from a given master.

Another object of the invention is a new and improved offset printing machine comprising a blanket cylinder which includes an adjustable line selector device for preventing printing of all but selected lines of text from a master to a work sheet.

Other and further objects of the present invention will be apparent from the following description and claims and are illustrated in the accompanying drawings which, by way of illustration, show preferred embodiments of the present invention and the principles thereof and what is now considered to be the best mode for applying those principles. Other embodiments of the invention embodying the same or equivalent principles may be used and structural changes may be made as desired by those skilled in the art without departing from the present invention.

In the drawings:

Fig. 1 is a perspective view of a planographic offset printing machine constructed in accordance with one embodiment of the invention;

Fig. 2 is a substantially simplified elevation view of the printing machine of Fig. 1;

Fig. 3 is an enlarged perspective view of the blanket cylinder of the planographic printing machine of Fig. 1;

Fig. 4 is an enlarged cross sectional view of the blanket cylinder of Fig. 3;

Fig. 5 shows a planographic master which may be utilized in the offset printing machine of the invention in connection with a particular kind of systems job;

Fig. 6 illustrates one printed form which may be reproduced in the printing machine utilizing the master of Fig. 5;

Fig. 7 illustrates another printed form which may be reproduced using the master of Fig. 5;

Fig. 8 shows yet another printed form which may be reproduced from the master of Fig. 5;

Fig. 9 is a perspective view of another embodiment of a blanket cylinder constructed in accordance with the invention; and

Fig. 10 is a cross section view of the blanket cylinder of Fig. 9.

Figs. 1 and 2 illustrate a rotary planographic offset printing machine 20 constructed in accordance with one embodiment of the invention. The printing machine 20 comprises a pair of spaced frame plates 22 which are mounted upon a suitable base 21. A form cylinder 25, a blanket or offset cylinder 26, and a platen or impression cylinder 27 are rotatably mounted between the frame plates 22 for cooperation with each other in the usual manner. A paper feed table 28 is provided to afford a means for introducing work sheets into the nip of the offset and platen cylinders 26 and 27. The several cylinders may be driven by a suitable motor through driving belts, pulleys, and like means in conventional manner.

A planographic form or master is mounted upon the cylinder 25 and is inked by a suitable inking mechanism which may, for example, include a pair of form rolls

35 which receive ink from an ink fountain (not shown) mounted within the housing 36 and which transfer the ink to the planographic master. An aqueous ink repellent is applied to the planographic plate in conventional manner by a repellent applicator roll 38 which is supplied with the ink repellent by a supply system (not shown) mounted within a housing 39. It will of course be understood that the above described general organization of parts of the printing machine is provided solely for the purpose of illustration and that the location and construction of the several different parts of the printing machine may be varied substantially without in any sense departing from the invention.

One embodiment of the blanket cylinder and adjustable line selector device of the invention is best illustrated in Figs. 3 and 4. As shown therein, the line selector device comprises a mask M and clamping means for the mask M, the clamping means comprising a pair of rectangular plates 41a and 41b facing each other. A plurality of pointed pins 60 are mounted on and extend from the inner surface of the plate 41a into a corresponding plurality of holes 60a in the plate 41b. The two plates 41a and 41b form the two arms of a clamp and are hinged upon a spindle 42. The support means for the clamp comprises a Z-shaped sliding bracket 45 (see Fig. 4) having an upper panel 43 which is secured to the plate 41a and further having a lower shelf 44, the ends of which are bent upwardly on either side to form two handles 58 which may be clasped by the machine operator between thumb and forefinger in order to shift the clamp laterally of the blanket cylinder 26.

The center panel of the Z-shaped sliding bracket 45 is secured, by means of a pair of square-sectioned studs 47 and pressure springs 49, to a sliding means for guiding movement of the mask M relative to the blanket cylinder. The sliding means comprises a rectangular rail 46 which is provided with a longitudinal slot 51 in which the square-sectioned portions of the studs 47 are engaged for sliding movement, the width of the square portions of the stud being only very slightly smaller than the width of the groove 51. Each of the springs 49 is compressed between a cup washer 52, which bears upon an adjusting nut 48 threaded upon the stud 47, and a washer 53 which engages the rear face of the rail 46. Accordingly, the springs 49 maintain the center panel of the sliding bracket 45 in bearing contact with the rear face of the rail 46, permitting the bracket to slide along the rail in frictional contact therewith. Moreover, the springs 49 tend to hold the plates 41a and 41b in firm engagement with each other, since the plate 41b, being freely hinged on the shaft 42, rests upon a blanket clamp 54b, while the plate 41a is pulled against the plate 41b when the sliding bracket 45 is brought to bear against the rail 46 by the biasing action of the springs 49.

The mask M is held in position, on the one hand, by the pressure of the clamping plates 41a and 41b against one another, and, on the other hand, by the pointed pins 60 projecting from the inner face of the plate 41a. The line selector device further comprises a means for marking or indexing the position of the mask and clamp on the rail; that is, the device includes a means for accurately locating the mask M at a series of different positions axially of the blanket cylinder. The position marking means comprises a pointer or index marker 50 which is preferably located in the middle of the lower shelf 44 of the sliding bracket 45. A graduated angle scale is employed in connection with the position pointer 50; the scale structure comprises a support portion 69 which is secured to the trailing clamp 54a for the blanket 55 by means of a pair of knurled screws 56 and lock nuts 57. The scale structure further includes a vertical portion 59, disposed at a right angle with respect to the support portion 69, which is marked with graduations corresponding to individual lines of data as described more fully hereinafter.

A spring blade 61 with a downwardly extending catch 65 at its free end is secured to the middle portion of the clamping plate 41a, being located so that its free end is maintained in contact with the upper edge of the rail 46.

5 The arrangement is such that the catch 65 engages in one of a series of positioning notches 66 in the top edge of the rail 46 whenever the register pointer 50 is aligned with a particular graduation on the scale 59. The engagement of the catch 65 in the positioning notch 66 prevents 10 lateral movement of the mask and clamp along the rail, thereby preventing any undesirable shifting of the mask which could otherwise take place during operation of the printing machine, for instance as a result of vibrations. The two ends of the rail 46 are affixed to the lead end 15 blanket clamp 54b by suitable means such as the two screws 62.

For a better understanding of the advantages offered by the blanket cylinder and movable mask construction of the invention, reference may best be had to a particular 20 printing application which may be carried out by the printing machine 20. One such application, in which the invention is highly advantageous, is the printing of production orders for the manufacture of a particular device or apparatus.

25 In many instances, the manufacture of the various parts of a given device, or the assembly of the parts constituting a device, involves the preparation of a series of different forms. In some instances, only one copy of each form may be required, whereas in others duplicate 30 or other multiple copies may be necessary, depending to a substantial extent upon the prevailing system in the factory in which the device is manufactured. In general, however, the system requires one or several copies of a repetitive document 70 (Fig. 6), commonly known as 35 a route sheet or job sheet, which may include a description 71 of the item to be manufactured, referred to hereinafter as "repetitive data," and a list 72 of the individual operations which must be performed in the different manufacturing departments of the factory, referred to hereinafter as "variable data." The route sheet or sheets 70 are accompanied by a set of smaller sheets or tickets, usually known as labor tickets or job tickets, each corresponding to a particular operation to be performed in one factory department; examples of such job tickets, comprising the printed cars 74 and 75, are illustrated in Figs. 7 and 8. For control purposes, however, the job tickets such as cards 74 and 75 should also show at least some description of the work piece; that is, the job tickets should include at least a portion of the repetitive data 71. Using the improved blanket cylinder 40 and selector mask arrangement of the present invention, the copies required for initiating particular manufacturing activity are processed as follows:

45 A planographic master 76, preferably a paper master 55 of the kind described in the aforementioned Worthen patent, is first prepared. As indicated in Fig. 5, the master includes two data sections on which information is typed or otherwise inscribed. The right-hand section 77 of the master receives the repetitive data 71 including, for example, a description of the device to be manufactured, an identifying number for the device being manufactured, a drawing number, the starting date for the manufacturing activity, the scheduled finishing date, the quantity of devices to be manufactured, specifications for the materials to be employed, and other like information. The left-hand section 78 of the master, which may, for example be separated from the section 77 by a perforated line 79, receives the variable data comprising the list of individual operations 72. Each of the items 50 in the variable data may include, for example, an operation identification number, a work shop number, a description of the operation to be performed, a machine tool code number, the set-up time for the machine tool, the work time for fabrication per piece, and other like data. 55 Each of these entries in the operation list 72 may com-

prise one or several lines; the space required for each line corresponds to the spacing of the index markings on the graduated scale 19.

After the master 76 has been prepared, it is mounted upon the form cylinder 25 and inked in the usual manner. It should be noted that the lines of data on the master 76, as mounted on the form cylinder 25, extend circumferentially of the cylinder; that is, they extend in the direction of rotational movement of the cylinder, as indicated by arrows A, Figs. 1 and 5. The ink images of the repetitive and variable data are then transferred from the planographic master to the blanket 55.

To print the route sheets 70, work sheets comprising blank or pre-printed paper are automatically fed through the printing machine 20, the number of work sheets corresponding to the number of documents required for distribution to various departments of the manufacturing company. For this portion of the printing operation, the mask M is preferably removed from the clamp 41a, 41b, leaving the entire blanket 55 unobstructed and unmasked. Consequently, both the repetitive data 71 and the variable data 72 are printed complete upon the route sheets, affording an overall description of the apparatus to be manufactured and of each of the several steps involved in the manufacture thereof.

The operator of the machine then mounts the mask M in place, securing the mask between the two clamp members 41a and 41b. The mask itself is preferably made of a relatively thin flexible material and may comprise, for example, a simple sheet of thin flexible card stock or other paper or of fabric. The work tickets, as exemplified by job tickets 74 and 75 are then fed into the printing machine 20. At the outset, selected portions of the variable information 72 are printed on the job tickets. The repetitive data printing of the job tickets is deferred until after printing of the variable data thereon, as explained more fully hereinafter. This sequence of printing the variable and repetitive data is necessary to effective operation of the printing machine, since otherwise the repetitive data would be imprinted on the face of the mask M during printing of the variable data and would produce a multi-image imprint in the repetitive data area of the job tickets.

In printing the variable data on the job tickets the master is inked and the ink image thereof is transferred to the blanket 55. Only one inking is normally required for printing the variable data on all job tickets, since only a few copies of each job ticket are necessary. The mask M is then positioned, with respect to the blanket cylinder 26, so that it does not cover any of the variable data, but may cover the repetitive data. The first job ticket is then fed into the printing machine from a position such that only the first item of variable information is imprinted thereon, the length of the job ticket being such that the remainder of the variable data is not imprinted on the job ticket. During this and subsequent variable-data runs of the job tickets, the master cylinder 25 is maintained in spaced relation with respect to the blanket cylinder 26, since no additional inking of the blanket cylinder is required.

After the end of one or more printing cycles, depending upon the number of job tickets required for the first item of variable information, the adjustable line selector device is moved by the machine operator, to the left as seen in Figs. 1 and 3, the required space for covering the first variable entry with the mask M. The second labor ticket is then fed into the machine and the second entry of variable information is printed thereon. As before, all undesired items of variable information are effectively omitted from the job ticket by virtue of the positioning of the mask M and the relatively short length of the job ticket. This printing process is repeated thereafter for each subsequent item of variable information, the desired number of job tickets being printed for each manufacturing, stocking, assembling, or other operation.

Operation of the adjustable line selector is extremely simple and convenient and requires a minimum of skill on the part of the machine operator. Thus, in order for the operator to insert the edge of the mask M between the retaining clamp plates 41a and 41b, it is only necessary to press downwardly (see Fig. 4) on the shelf 44 of the sliding bracket 45 so as to move the lower part of the bracket easily from the rail 46 against the biasing action of the springs 49. In the course of this action, the clamping plate 41a, which is integral with the sliding bracket 45, is lifted, whereas the plate 41b remains in position on the blanket clamp 54b by virtue of its own height and the fact that it is freely hinged upon the shaft or spindle 42. After insertion of the mask M, when the operator releases the bracket shelf 44, the springs 49 again press the clamp plate 41b against the plate 41a and hold the mask M tightly clamped between the inner surfaces of the plates. Moreover, the pointed pins 60 perforate the mask and penetrate therethrough into engagement with the apertures 60a in the clamp plate 41b. The operator then clasps the handles 58 at the ends of the shelf 44 on the Z-shaped sliding bracket 45, usually between the thumb and forefinger, and shifts the bracket laterally along the rail 46 while exerting sufficient outward pulling force to disengage the catch 65 from the notch 66 in which it has been engaged. In this manner, the operator may slide the catch along the upper edge of the rail 46 until it is located above the notch corresponding to the desired position for the mask, after which the handles 58 are released and the spring action of the blade 61 forces the catch 65 into the desired notch 66. Alignment of the mask is made simple and convenient by registration of the pointer 50 with the graduations on the scale 59.

In printing of the job tickets, the operator next positions, on the feed table, the labor ticket which is to be imprinted with the line or lines of variable information corresponding to the first item of variable data. In order to align the job ticket with the desired portion of the variable information data and with the mask M, a graduated scale 64 is preferably provided upon the feed table 63 of the printing machine, the scale 64 corresponding to the graduations of the blanket cylinder mask scale 69. In this manner, once the operator has positioned the labor ticket 120 so that the bottom edge of the ticket (the left edge to the operator) covers the graduations up to but not including the index marking n, the ticket may be fed into contact with the blanket cylinder 26 in a position such that the space at the bottom of the ticket is located exactly opposite the desired item of variable information transferred from the master onto the blanket. No other information can be printed on this labor ticket because, on the one hand, the data transferred from the master onto the blanket beneath the item of variable information corresponding to index marking n, that is to the left as seen in Fig. 3, these additional data (n+1), (n+2) are located beyond the bottom edge of the ticket in an area of the blanket cylinder which does not contact any portion of the paper. On the other hand, the other variable information entries (n-1), (n-2) which are located above the item n, that is, to the right as seen in Fig. 3, cannot be printed because of the interposition of the mask M between the blanket and the labor ticket, the left edge of the mask being located just above the variable data n when the pointer 50 has been set by the operator in alignment with the graduation n on the scale 19.

To imprint the next item of variable information (n+1) on the next labor ticket, the operator shifts the sliding bracket 45 to the left along the rail 46 until the pointer 50 is aligned with the graduation (n+1) upon the scale 59, as described hereinabove. He then positions the job ticket to be printed on the feed table, using the scale 24 to align the ticket so that when it is fed into the machine only the desired item (n+1) is printed thereon. In this manner, and as described hereinabove, each

7
job ticket is imprinted with only the desired portions of the variable data.

After the printing of the variable data 72 has been completed, the repetitive data 71 is reproduced on the job tickets such as the cards 74 and 75. For this purpose, the master cylinder 25 is again actuated to transfer an ink image onto the blanket 55 of the blanket cylinder 26. Inasmuch as printing of the variable data has been completed, the variable data portion of the master may be removed prior to this inking step, in the event that a detachable-section master is utilized. This is not essential, however. Moreover, if desired, a master overlay may be employed to block out the variable-data portion of the master and prevent re-inking of the variable data on the blanket, thus precluding reproduction of the variable data on the job tickets in their second run through the machine.

In printing of the repetitive data 72 on the job tickets, the tickets are fed through the right-hand side of the printing machine 29, as viewed in Fig. 1. As an alternative to the arrangements set forth immediately hereinabove, the variable and repetitive data areas of the master may be separated by a spacing sufficient that the relatively short job tickets are not imprinted with the variable data at the time that the repetitive data is reproduced thereon. Normally, it is necessary to reproduce a total number of job tickets which is greater than the number which may be imprinted from a single inking of the blanket 55. Consequently, it is usually necessary to re-ink the blanket 55 a number of times in the course of printing of the repetitive data 71. Thus, printing of the repetitive data on the job tickets is carried out in a manner essentially similar to printing of the route sheets, except for the provisions described hereinabove for preventing simultaneous printing of the variable data 72.

Figs. 9 and 10 illustrate another embodiment of the invention in which the adjustable line selector device is of somewhat modified construction. In this construction, the clamp supporting means comprises an angle bracket 93 having one flange which is secured to the clamp plate 41b and having a second flange which is attached, as by means of the screws 94, to the sliding mount for the clamp. In this instance, the sliding mount comprises a U-shaped slide member 95 which engages a rectangular rail 96, the rail 96 extending longitudinally of the blanket cylinder 26. A spring member 97 is mounted upon the slide member 95 and is compressed between the inner rear face of the slide member 95 and the front face of the rail 96, as best seen in Fig. 10. The spring 97 pulls the inwardly bent flanges at the ends of the two side walls of the slide member 95 in contact with the rear or upper face of the rail 96.

The line selector device further includes a shield member 98 having a forwardly bent lower end 99, the shield being mounted upon the upper clamp plate 41a as illustrated in Fig. 10. A spring blade 100 is secured to the bottom face of the U-shaped slide member 95, as by means of a screw 101, and engages the upper or rear face of the shield 98. The mask clamp in this embodiment thus comprises two members, one being formed by the upper clamp plate 41a and the shield 98 to which it is affixed and the other by the lower plate 41b, the angle bracket 93 mounted thereon, and the slides 95 to which the angle bracket is affixed. The spring blades constantly urge the plates 41a and 41b toward each other. To insert the mask M between the blades, the operator pushes against the shield 98, moving the shield against the action of the spring 100 and toward the slide member 95, thereby separating the plates 41a and 41b and providing adequate space for insertion of the edge of the mask. In this device, it should be noted that the mounting pins 60 of the first embodiment have been omitted; these pins may be desirable in some instances but are not essential inasmuch as the spring biasing means in either embodiment may afford sufficient gripping strength

to maintain the mask M in the desired position on the blanket cylinder.

The line selector device in the embodiment of Figs. 9 and 10 is also provided with marking or indexing means for locating the slide member 95 in predetermined accurate position along the rail 96, the indexing means being substantially similar to that described hereinabove in connection with Figs. 3 and 4. Thus, the position marking means comprises a pointer 50' which in this instance is located in the middle of the downwardly extending portion 99 of the shield member 98 (see Fig. 10), in position to cooperate with the graduated scale 59 of the printing machine. The shelf 99 of the shield 98 also has its left and right ends 58' bent upwardly to form two handles which may be clasped by the operator, usually between the thumb and forefinger, to shift the slides along the rail 96 and to bring the pointer 50' opposite a graduation on the scale 59, that is, in alignment with the figure corresponding to a particular line selection. The rail 96 may be secured to the lead end blanket clamp 54b of the blanket cylinder as by means of two countersunk set screws 62', lock nuts 61' being utilized to maintain the screws in position in the rail 96 and the blanket clamp 54b.

While preferred embodiments of the invention have been described and illustrated, it is to be understood that these are capable of variation and modification. Accordingly, the aim in the appended claims is to cover all such variations and modifications as may fall within the true spirit and scope of the invention.

I claim:

1. In an offset printing machine of the kind comprising a form cylinder adapted to mount a lithographic master, an impression cylinder, a feed table and a blanket cylinder interposed between the form and impression cylinders to transfer an ink image from a master mounted on said form cylinder to a print-receiving sheet fed from said feed table between said blanket and impression cylinders, a line selector device comprising: a slide member mounted on said blanket cylinder for longitudinal sliding movement with respect thereto; a clamp, affixed to said slide member, for gripping a thin, flexible mask and supporting said mask in position to cover a predetermined portion of said blanket and prevent printing therefrom; first index means on said blanket cylinder for indicating the portion of said blanket cylinder covered by a mask supported in said clamp; and second index means on said feed table for enabling an operator to align a print-receiving sheet in predetermined position with respect to the masked and unmasked portions of the blanket cylinder.

2. In an offset printing machine of the kind comprising a form cylinder adapted to mount a lithographic master, an impression cylinder, a feed table and a blanket cylinder interposed between the form and impression cylinders to transfer an ink image from a master mounted on said form cylinder to a print receiving sheet fed from said feed table between said blanket and impression cylinders, a line selector device comprising: a slide member mounted on said blanket cylinder for longitudinal sliding movement with respect thereto; a clamp, comprising a pair of clamp plates, one of which is mounted in fixed position on said slide member and the other of which is pivotally mounted on said slide member, and resilient biasing means urging said pivotally mounted clamp plate toward said fixed clamp plate, for gripping a thin, flexible mask and supporting said mask in position to cover a predetermined portion of said blanket and prevent printing therefrom; first index means on said blanket cylinder, for indicating the portion of said blanket cylinder covered by a mask supported in said clamp; and second index means on said feed table for enabling an operator to align a print-receiving sheet in predetermined position with respect to the masked and unmasked portions of the blanket cylinder.

3. In an offset printing machine of the kind comprising

ing a form cylinder adapted to mount a lithographic master, an impression cylinder, a feed table and a blanket cylinder interposed between the form and impression cylinders to transfer an ink image from a master mounted on said form cylinder to a print-receiving sheet fed from said feed table between said blanket and impression cylinders, a line selector device comprising: a guide rail mounted on said blanket cylinder and extending longitudinally thereof; a slide member mounted on said guide rail for longitudinal sliding movement with respect thereto; resilient biasing means, effectively engaging said slide member and said guide rail, for maintaining said slide member in frictional contact with said rail; a clamp affixed to said slide member, for gripping a thin, flexible mask and supporting said mask in position to cover a predetermined portion of said blanket and prevent printing therefrom; first index means on said blanket cylinder, for indicating the portion of said blanket cylinder covered by a mask supported in said clamp; and second index means on said feed table for enabling an operator to align a print-receiving sheet in predetermined position with respect to the mask and unmasked portions of the blanket cylinder.

4. The method of printing a series of related documents comprising the following steps: applying repetitive and variable ink-receptive data images to first and second discrete areas of a lithographic master, said variable data being arranged in a series of equally spaced lines; mounting said master on a form cylinder with the lines of variable data extending circumferentially thereof; inking the images on the master; rotating the form cylinder in ink-transferring contact sheet with a cylindrical blanket; feeding work sheets having lengths correlated to the data on the master one-by-one between said blanket and a platen cylinder from a series of different positions therealong while simultaneously masking predetermined related portions of said blanket at one side only of the work sheet to imprint only one item of variable data on one marginal portion of each work sheet; and feeding said work sheets one-by-one between said blanket and said platen cylinder from a fixed position to imprint said repetitive data on each work sheet adjacent the opposite edge thereof.

5. The method of printing a series of related documents comprising the following steps: applying repetitive and variable ink-receptive data images to first and second discrete areas of a lithographic master, said repetitive data area having a given length and said variable data being arranged in a series of equally spaced lines; mounting said master on a form cylinder with the lines of variable data extending circumferentially thereof; inking the images on the master; rotating the form cylinder in ink-transferring contact with a cylindrical blanket; feeding work sheets having lengths correlated to the data on the master one-by-one between said blanket and a platen cylinder from a series of different positions therealong while simultaneously masking different predetermined portions of said blanket at one side only of the work sheet to imprint only one item of variable data on each work sheet, said work sheets being selected to correspond in length to the variable data entries imprinted thereon; and feeding said work sheets one-by-one between said blanket and said platen cylinder from a fixed position to imprint said repetitive data on each work sheet.

6. In an offset printing machine of the kind comprising a form cylinder adapted to mount a lithographic master, an impression cylinder, a feed table and a blanket cylinder interposed between the form and impression cylinders to transfer an ink image from a master mounted on said form cylinder to a print-receiving sheet fed from said feed table between said blanket and impression cylinders, a line selector device comprising: a guide rail affixed to and extending longitudinally of said blanket cylinder and having a central longitudinal slot therein; a slide member

mounted on said guide rail for longitudinal sliding movement with respect thereto, said slide member comprising a Z-shaped bracket and a plurality of studs affixed thereto and extending into said guide rail slot; a corresponding plurality of biasing springs, individually mounted on said studs and engaging said studs to urge said bracket into frictional contact with said rail; a clamp, affixed to said slide member, for gripping a thin, flexible mask and supporting said mask in position to cover a predetermined portion of said blanket and prevent printing therefrom; first index means on said blanket cylinder for indicating the portion of said blanket cylinder covered by a mask supported in said clamp; and second index means on said feed table for enabling an operator to align a print-receiving sheet in predetermined position with respect to the masked and unmasked portions of the blanket cylinder.

7. In an offset printing machine of the kind comprising a form cylinder adapted to mount a lithographic master, an impression cylinder, a feed table and a blanket cylinder interposed between the form and impression cylinders to transfer an ink image from a master mounted on said form cylinder to a print-receiving sheet fed from said feed table between said blanket and impression cylinders, a line selector device comprising: a guide rail affixed to and extending longitudinally of said blanket cylinder and having a plurality of index notches spaced at preselected intervals therealong; a slide member mounted on said guide rail for longitudinal sliding movement with respect thereto; a clamp, affixed to said slide member, for gripping a thin, flexible mask and supporting said mask in position to cover a predetermined portion of said blanket and prevent printing therefrom; first index means on said blanket cylinder for indicating the portion of said blanket cylinder covered by a mask supported in said clamp and comprising a graduated scale corresponding to said index notches; latch means comprising a resilient releasable latch member mounted on said slide in position to engage one of said index notches whenever said slide is in predetermined alignment with the corresponding portion of said scale; and second index means on said feed table for enabling an operator to align a print-receiving sheet in predetermined position with respect to the masked and unmasked portions of the blanket cylinder.

8. In an offset printing machine of the kind comprising a form cylinder adapted to mount a lithographic master, an impression cylinder, a feed table and a blanket cylinder interposed between the form and impression cylinders to transfer an ink image from a master mounted on said form cylinder to a print-receiving sheet fed from said feed table between said blanket and impression cylinders, a line selector device comprising: a slide member mounted on said blanket cylinder for longitudinal sliding movement with respect thereto; a clamp, affixed to said slide member, for gripping a thin, flexible mask and supporting said mask in position to cover a predetermined portion of said blanket and prevent printing therefrom; first index means, including a first graduated scale mounted on and extending axially of said blanket cylinder, for indicating the portion of said blanket cylinder covered by a mask supported in said clamp; and second index means on said feed table comprising a second similar graduated scale mounted in parallel relation to the axis of said blanket cylinder in predetermined axially displaced alignment with said first scale to enable an operator to align a print-receiving sheet in predetermined position with respect to the masked and unmasked portions of the blanket cylinder.
